UNITED STATES PATENT OFFICE.

GEORGES CLOETENS, OF BRUSSELS, BELGIUM.

WIND MUSICAL INSTRUMENT.

Application filed November 10, 1922. Serial No. 600,162.

To all whom it may concern:

Be it known that I, GEORGES CLOETENS, a subject of the King of the Belgians, and resident of Brussels, Belgium, have invented certain new and useful Improvements in or Relating to Wind Musical Instruments, of which the following is a specification.

The invention relates to an improvement in reed wind musical instruments and is more particularly applicable to a device for permitting the expression of the musical sound produced to be modified by the touch or operation of the keys.

In known devices of this character the expression of the musical sound is modified by placing the instrument in a chamber of which the walls are provided with shutters which may be opened to a greater or less extent in such a manner as to permit of the musical sound to be emitted from the chamber with greater or less expression or intensity.

The invention has for its object to obviate the use of this chamber and to vary the expression of the musical sound by varying the depression of the keys.

According to the present invention the vibration of each reed is adjusted by a member actuated by the variations in the pressure of the air which causes the reed to vibrate. This member preferably comprises a bellows arranged on the trunk which supplies the air to the reed in question. The bellows acts as a spring the tension of which varies with the pressure of air admitted thereto.

The accompanying drawings illustrate by way of example a number of forms of construction of the invention.

Fig. 1 illustrates a stop of reed organs with flaps or hinges in sectional elevation.

Fig. 2 illustrates an organ stop similar to that illustrated in Fig. 1, but according to another method of construction.

Fig. 3 shows an organ stop similar to that illustrated in Figs. 1 and 2 but operated by air suction.

Figs. 4 and 5 illustrate an organ stop in which the reed itself forms one of the walls of the bellows.

Figs. 6 and 7 illustrate cross sectional elevations of ordinary vibrating reeds to which devices according to the invention are applied, and

Figs. 8 and 9 illustrate two vibrating reeds, connected together, showing two characteristic positions during their operation.

In these drawings, the same reference numerals indicate the same or similar parts.

In the organ stop operated by compressed air illustrated in Fig. 1 the key when pivoting on its support 2 raises a controlling valve 3 which is normally held downwards by a spring 4.

In proportion to the lift of this valve 3 more or less compressed air blows from the chamber 5 into the trunk 6, so that the pressure of air in the trunk 6 varies according to the amount of depression of the corresponding key of the reed in question.

The reed illustrated is of a type known as hinged or supported vibrating reed, the reed comprising a chamber 7 open on one side, and a plate 8 of suitable material, preferably of thick glass which bears freely on the walls of this chamber in such a manner as to cover the open side, and being held in place by hinges 19. A spring 20 tends to hold the plate 8 on the walls of the chamber 7. The pressure which exists in the said chamber causes the plate 8 to vibrate in such a manner as to produce a solemn and intense sound.

The compressed air passes from the trunk 6 into the interior of the chamber 7 through an aperture 9 and produces more intense vibrations of the plate 8 in proportion as the pressure in the interior of the chamber 7 increases.

When the plate 8 is raised the air escapes through the auxiliary chamber 10.

In order to return the plate 8 towards its seating a compensating device is employed according to the invention, the device being adapted to limit the number of vibrations of the plate 8 in order to maintain the reed in tune, in relation to the vibrations in pressure which occur in the interior of the chamber 7.

This compensating device comprises a bellows 11 which through the medium of the abutment 12 acts upon the plate 8.

Compressed air is conducted towards the bellows and tends to open same the air being conducted through an auxiliary conduit 13, in which the same pressure exists as in the trunk 6 so that the abutment 12 acts automatically on the plate 8, with a force pro-

portional and in the opposite direction to that which acts on the other side of the plate 8.

• Shutters or valve members 14 and 15 permit of adjusting permanently the passage of air under pressure which passes from the conduits 6 and 13 into the chamber 7 and the bellows 11.

Fig. 2 illustrates a device similar to that illustrated in Fig. 1, wherein use is made of two bellows one acting as the compensating device 11 and the other 16 as a spring corresponding to the spring 20 in Fig. 1. The compressed air is conducted into the interior of the bellows 11 by the auxiliary conduit 13 connected to the chamber 7.

The bellows 16 is in communication with the reservoir for compressed air (not shown) by means of the pipe or passage 17 in such a manner that the pressure of the bellows 16 upon the plate 8 is constant.

The shutters 15, 14 and 18 regulate the supply of air admitted into the interior of the chamber 7 and to bellows 11 and 16. A slider 21 controls the passage of the conduit 13 according to the pressure which exists in the interior of the bellows 11 the slider being connected to the bellows 11 by means of a hinge 22.

The plate 8 is held in place in this case not by a hinge, but by a simple bearing the plate 8 being slightly inclined and slid into a groove 23 provided in the wall 24 of the chamber 7.

Fig. 3 illustrates a device similar to that illustrated in Fig. 1 but operating by suction air, the air entering through the aperture 24 and passing out through the conduit 25. The same pressure exists in the bellows 11 the chamber 7 and the bellows 13.

Fig. 4 illustrates another form of construction of the device wherein the movable wall 8 of the bellows 11 serves as the vibrating plate of the chamber 7.

Moreover, a set of valves 26 and 27 is provided which control the admission and consequently the pressure of compressed air in the interior of the bellows 11. The valve 26 controls the passage from the conduit 17 terminating in a reservoir for compressed air, not shown, in the interior of which exists a suitable pressure. The valve 27 controls the communication between the bellows 11 and the chamber 7.

When the instrument is in a state of rest, the valve 26 is open and the bellows 11 passes with a constant pressure the plate 8 on the chamber 7, the valve 27 being closed. When the compressed air flows through the conduits 6 and 13, the valve 27 opens, and the pressure which exists in the bellows 11 is the same as that which exists in the chamber 7, and the valve 26 closes automatically.

Fig. 5 illustrates a form of construction

wherein the chamber 7 itself vibrates whilst the plate 8 remains in a position determined by the pressure which exists in the interior of the bellows 11. In this figure the auxiliary compressed air reservoir 28 is shown, which by means of the conduit 17 supplies the bellows 11 when the instrument is in a position of rest, in such a manner as to press the plate 8 against the walls of the chamber 7. This chamber itself is constantly pressed downwards by a weak spring 30, the chamber being capable of vibrating as a whole whilst being held in place, as it is connected to its support 31 by means of the hinge 32.

Fig. 6 illustrates the ordinary device of vibrating reeds comprising the foot 33, the nozzle 34, the blade 35 and the spring 36.

In the known devices the spring acts with constant pressure on the blade. In order that the spring 36 may bear with a variable pressure against the blade 35, according to the variations in the pressure of the air which enters into the foot 33 of the reed, a bellows device is provided which lightly relieves the tension of the spring 36, in proportion to the pressure of the air which causes the blade 35 to vibrate. For this purpose, the bellows 37 admits air at a variable pressure through the aperture 38 and this pressure tends to raise the bellows 37 and also the stem 39 which is provided with a hook 40 secured thereto. This hook engages the spring 36 and is adapted to move the spring upwards so as to reduce the tension with which it bears against the blade 35 when the pressure of the air which causes the latter to vibrate increases.

Shutters 41 and 42 regulate in a permanent manner the supply of air admitted into the interior of the foot 33 and into the interior of the bellows 37.

Fig. 7 illustrates a device similar to that shown in Fig. 6 and is particularly applicable in the case where it is desired to produce sounds of a shriller note. The inlet aperture 38 for the compressed air into the bellows 37 is located near the hinge of the latter, whilst in Fig. 6 the inlet aperture 38 is provided near the end of the bellows opposite to the end at which the hinge is located.

Figs. 8 and 9 relate to hinged vibrating reeds arranged in pairs and which are connected to a single admission trunk 6 in such a manner as to be vibrated by the same stream of air which is aspirated by the trunk 6 when the corresponding key is actuated. The trunk 6 is connected to chambers 43 and 44 of the vibrating reeds by conduits 45 and 46.

The two plates 47 and 48 are positively connected together by means of a rod 49. The air aspirated draws the plates 47 and 48 towards the interior of the chambers 43

and 44. This movement is counterbalanced by making the plates 47 and 48 of suitable weight and by a suitable spring 50. In the case where compressed air is used a suitable arrangement of the various elements produces the same result.

What I claim is:

1. A beating reed wind musical instrument, comprising, a beating reed, a conduit 10 for supplying compressed air to the reed, a key for controlling flow of compressed air in the conduit, and a member controlled by variations in the pressure of compressed air in the conduit, said member acting by pressing on that face of the reed opposite to the face submitted to the action of the compressed air, for automatically regulating the vibrations of the reed.
2. A beating reed wind musical instrument, comprising, a beating reed, a conduit 20 for supplying compressed air to the reed, a key controlling flow through the conduit, and a bellows communicating with the conduit, the bellows acting by pressing on that face of the reed opposite to the face submitted to the action of the compressed air, to automatically adjust the vibrations of the reed.
3. A beating reed wind musical instrument, comprising, a beating reed, a conduit, 30 a bellows communicating with the conduit and acting on the reed, and means for permanently adjusting the section of the passage establishing communication between the bellows and the conduit.
4. A beating reed wind musical instru-

ment, according to claim 3, said means comprising a hand operable shutter.

5. A beating reed wind musical instrument, comprising, a beating reed, a conduit 40 for supplying compressed air to the reed, an air reservoir connected to the conduit, a key controlling flow through the conduit, means automatically controlling vibration of the reed by variation in the pressure of the 45 air in the conduit, and means placing elastic tension on the reed in accordance with the pressure of air in the air reservoir.

6. An instrument according to claim 5, said means automatically controlling said 50 reed being a bellows, and said means placing tension on said reed being a bellows connected with said air reservoir.

7. A beating reed wind musical instrument, comprising, a beating reed, a conduit 55 for supplying compressed air to the reed, a key controlling flow through the conduit, a bellows communicating with the conduit and automatically controlling the vibration 60 of the reed according to variations of pressure in the conduit, a second bellows placing elastic tension on the reed, and a valve controlling the supply of air to the first said bellows, the valve being controlled by pressure variations in the first said bellows. 65

Signed at Brussels, Belgium this 25th day of October A. D. 1922.

GEORGES CLOETENS.
